US0D1072083S

(12) **United States Design Patent** (10) **Patent No.:** **US D1,072,083 S**
(45) **Date of Patent:** **** Apr. 22, 2025**

(54) **RACE CAR MODEL**

(71) Applicant: **Roberto Tomasi**, Brasov (RO)
(72) Inventor: **Roberto Tomasi**, Brasov (RO)

(**) Term: **15 Years**

(21) Appl. No.: **35/518,947**

(22) Filed: **Oct. 24, 2023**

(80) **Hague Agreement Data**

Int. Filing Date: **Oct. 24, 2023**

Int. Reg. No.: **DM/232762**

Int. Reg. Date: **Oct. 24, 2023**

Int. Reg. Pub. Date: **Nov. 10, 2023**

(51) **LOC (15) Cl.** **21-01**

(52) **U.S. Cl.**

USPC **D21/549**

(58) **Field of Classification Search**

USPC D21/419, 424, 427, 428, 431, 433, 434, D21/477, 483, 495, 533, 537, 539, 548, D21/549, 550-554, 556-562; D12/12, D12/19, 82, 83, 84, 85, 86, 87, 88, 90, D12/91, 93, 163, 167; 296/181.1, 181.5, 296/181.3, 183.1, 37.6; 446/448
